COMBINED SAND PAIL AND TRUCK TOY

William R. Selby, Jr., Chatsworth, Calif., assignor to Eldon Manufacturing Co., Los Angeles, Calif., a corporation of California

Application December 21, 1959, Serial No. 58,730

Term of patent 14 years

(Cl. D34—15)

Fig. 1.

Fig. 2.

FIG. 3.

FIG. 4.

FIG. 5.

Figure 1 is a top plan view of a combined sand pail and truck toy showing my new design.

I claim:

The ornamental design for a combined sand pail and truck toy, as shown.
